UNITED STATES PATENT OFFICE

108,342

DESIGN FOR A TOP SOCK OR SIMILAR ARTICLE

Ann Morrison, New York, N. Y.

Application December 31, 1937, Serial No. 74,008

Term of patent 3½ years

To all whom it may concern:

Be it known that I, Ann Morrison, a citizen of the United States of America, residing in city of New York, county of New York, and State of New York, have invented a new, original, and ornamental Design for a Top Sock or Similar Article, of which the following is a specification, reference being had to the accompanying drawing, forming part thereof.

Fig. 1 is a side view of a top sock or similar article showing my new design.

Fig. 2 is the opposite view of Fig. 1.

Fig. 3 is a rear view of the top sock.

I claim:

The ornamental design for a top sock or similar article, substantially as shown.

ANN MORRISON.
